UNITED STATES PATENT OFFICE.

DAVID L. FINE, OF DORCHESTER, MASSACHUSETTS.

GARMENT.

REISSUED

1,426,973.

Specification of Letters Patent. Patented Aug. 22, 1922.

Application filed November 28, 1917. Serial No. 204,446.

To all whom it may concern:

Be it known that I, DAVID L. FINE, a citizen of the United States, and resident of Dorchester, in the county of Suffolk and 5 State of Massachusetts, have invented a new and useful Garment, of which the following is a specification.

This invention relates to a garment, and pertains more particularly to a body covering, for the lower portions of the body, such as underskirts, petticoats, bloomers, knickerbockers, drawers, or the like. The invention has for its special object and application a proper and efficient means for supporting 10 a divided, bifurcated or separated garment or skirt at the point of suspension along the waist-line of the body.

In order to illustrate my invention I have shown in the accompanying drawing 20 but a single embodiment thereof, wherein:

Fig. 1 is a perspective view of a body garment herein consisting of a pair of bloomers with the invention applied thereto.

Fig. 2 is a side elevation of the upper 25 portion of the said bloomers.

Fig. 3 is a perspective view of a modified form of said garment, and

Fig. 4 is a side elevation of the upper portion of the garment shown in Fig. 3.

30 The terms employed herein are used in the generic and descriptive sense to indicate elements, and are not therefore specifically or primarily intended as terms of limitation.

35 In the drawing 10 in its entirety designates a body covering for the lower portions of the body. Herein, for convenience, the said covering is shown as a pair of ladies' bloomers, knickerbockers or the like, 40 but for all practical purposes the covering may be an over or underskirt, drawers or such other articles of apparel as are adapted to be supported, suspended or hung from the waist-line of the wearer. Such 45 garments may be divided or separated at one or more points along the waist-band to permit of the passage of the body therethrough.

After the garment has been fastened to the 50 body by the usual types of waist-bands, it frequently becomes necessary to unfasten the entire supporting band to permit displacement of a portion of the garment. This is especially the case where the garment

is of the closed or bifurcated type. That is, 55 for example, it separately and completely encloses each limb and the body as in the case of bloomers, knickerbockers, trousers, drawers and the like.

The bloomers illustrated by Figs. 1 and 2 60 are parted at 15 along each side from the waist-band 16 to a point just below or preferably below the hips at 17. Herein the waist-band consists of a body or waist encircling portion shown in the various figures 65 and adapted to be joined or fastened together at 18 by means of the stud and socket clasps 19 and 20. As illustrated the said junction is preferably at the middle of the back; thus, in Figs. 1 and 2, providing said 70 band 16 with two straps 21 and 22, and in Figs. 3 and 4 with extensions 23 and 24 projecting from each side 25 of the forepart 26 of the garment to said middle point. The said junction, however, may be 75 at either side 25, thus providing for but one long strap or extension adapted to fasten by means of said clasps to the forepart 26 at the side opposite the permanent junction of the strap with said body. That is, the 80 element forming the encircling portion about the abdomen, may be formed integral with the garment or may pass through a hem or beading 27 formed for that purpose.

Referring to Figs. 1 and 2, the waist-band 85 16 is in the form of a hem or beading 27 enclosing the abdominal strap or band 28, preferably of an elastic or yielding nature of less length than the beading 27 when extended. Therefore, when the abdominal 90 band 28 is in the normal or retracted condition, the beading 27 is Shirred, gathered or tucked to conform to the said normal length or condition of said abdominal band 28. The said straps 21 and 22 may be non- 95 elastic and joined permanently to the side edges 25 of the forepart 26 and to the said abdominal band 28. This makes the waist-band consisting of the straps 21 and 22, or the abdominal band 28, as a unit from 100 which the forepart 26 of the garment is suspended or hung.

Thus it will be seen that when the studs 19 and sockets 20 are snapped together after placing the band about the waist or body, 105 that there is a complete encircling waist-band supporting the said forepart 26 which does not require removal until the garment

is taken off the body. Therefore, said forepart 26 always remains in its proper place and does not drop or displace when other portions of the garment other than said waist-band herein are unfastened for displacement.

For example, the top of the rear drop-flap 30 extends up and along the waist-line when the forepart of the garment and straps 21 10 and 22 are fastened to the body. Said flap is provided with any preferred type of waist-band. As illustrated, the same consists of a hem or beading 31 through which is an elastic band 32 or the like, the ends of 15 which are secured to the sides 33 of said flaps by stitching or any other form of fastening. Said elastic band 32, when in the normal or retracted state, is shorter than the top length of said beading 31 when extended so as normally to maintain the beading in a gather or tucked condition, the same as in the case of the forepart beading 27.

At each side of said flap at the waist-line or the termination of the waist-band is a 25 socket 35 adapted to engage the stud 36 at each side edge 25 of the forepart 26.

In Fig. 1 the said flap 30 is illustrated as unclasped from the forepart 26 so that the former may be lowered to a point below 30 the hips when necessary, leaving said forepart 26 and waist-band or straps 21 and 22 encircling the body to support the said forepart. When it is desired, the flap 30 is raised and the respective sockets 35 are 35 snapped onto the studs 36 to properly support said flap 30 and entirely enclose the body.

By employing an elastic strap 28 about the abdominal portion of the waist-band, there 40 is provided an automatic yielding or adjustable feature co-operating with the said straps 21 and 22 to permit the entire supporting band to snugly fit the body. Likewise, the elastic strap 32 at the waist-band 45 of the flap 30 provides an automatic yielding or adjustable feature enabling the said flap to snugly fit across the back of the body.

In Figs. 3 and 4 the body covering illustrated, is provided with the extensions 50 23 and 24 of any shape or design projecting from the sides 25 to the middle portion of the back at 18. Preferably, said extensions are of triangular shape, the top portion of 55 which may properly perform the functions of the straps 21 and 22. That is, the extensions may be unyielding, as in the case of said straps and joined to the forepart 26 along the parting 15. On the other hand, the beading 27 and strap 28, may be continued to the junction point 18 to form a 60 continuous elastic supporting band for said forepart 26. The flap 30 is secured to the said forepart 26 at the sides 25 and in the same manner as in Figs. 1 and 2.

65 As before stated, all straps, bands or the

extensions 23 and 24 may be non-elastic and fitted to the actual dimensions of the body without altering the nature of the invention.

By the employment of my invention, improper or bungling replacement of an under garment of this class is eliminated, and all parts not necessary to remove or displace are not disturbed once the garment is in place on the body and an overskirt covers the 75 same. That uncomfortable and unsightly bunching of the clothing is obviated and a garment of the utmost utility and convenience is provided.

I have described herein one embodiment 80 of my invention, but it is to be understood that the latter is not essentially limited to the specific construction and organization of said embodiment, since the same may be varied without departing from the proper 85 scope of the claims.

Having thus described my invention in detail, what I claim as new is:

1. In a waist supported garment, a body covering having the top portion 90 thereof divided at the hip sections of the same to form a forepart and a drop-flap, said forepart being provided at the waist-line thereof with an elastic band having the ends thereof permanently secured at the ends 95 of said forepart with the intermediate parts of said forepart slidably supported on said elastic band to effect a gathering feature to said forepart, and retaining means extending rearwardly beyond said forepart for 100 engaging the same in supported relation about the waist of the wearer, and said drop-flap being also provided at the waistline thereof with an elastic band having the ends thereof permanently secured to the sides of 105 said drop-flap with the intermediate portions of said drop-flap slidably supported on said last mentioned elastic band for effecting a gathering and self-contracting feature for the waistline of said drop-flap; and co-acting fastening means provided at the sides 110 of said forepart and said drop-flap at the waistline sections thereof, adapted to temporarily support said drop-flap in wearing relation with said forepart of said garment. 115

2. In a garment, a body covering divided at each side thereof from the top or waistline to a point below the hips to form a forepart and a drop-flap, said forepart being provided at the waistline thereof with an 120 elastic band having the ends of said band permanently connected to the ends of said forepart with the intermediate section of said forepart slidably supported on said elastic band for effecting a self-gathering 125 feature to said forepart, and said drop-flap being provided at the waistline thereof with an elastic band which is also permanently secured at the ends thereof with the sides 130 of said drop-flap with the intermediate sec-

tion of said drop-flap slidably supported on said elastic band to provide a self-gathering and self-contracting feature for the waistline of said drop-flap; a pair of straps secured 5 to and extending from each side of said forepart adapted to be joined together to form an encircling member about the waist of the wearer to support the garment in wearing relation with the body; and coacting fastening means provided said forepart 10 and said drop-flap at the upper points of division of same, adapted to temporarily secure said drop-flap in closed relation with said forepart.

DAVID L. FINE.
